WILLIAM A. JONES, OF WESTERLEIGH, NEW YORK, ASSIGNEE TO THE BABCOCK & WILCOX COMPANY, OF BAYONNE, NEW JERSEY, A CORPORATION OF NEW JERSEY

STEAM BOILER AND CONDENSER FOR VAPOR FROM HIGH BOILING POINT LIQUIDS

Application filed July 24, 1928. Serial No. 234,957.

This invention relates to a water tube steam boiler in which the steam is generated by the latent heat of condensation of the vapor of a high boiling point liquid. The generating surfaces of the steam boiler are enclosed into a cylindrical shell into which the vapors are introduced and condensed.

An object of the invention is to provide a steam boiler wherein the steam generating surface or heat absorbing unit is heated by a vapor from a high boiling point liquid, and in which, by reason of the differences in temperature between the respective parts, it is essential to adequately care for the relative expansion and contraction of the composite parts.

A further feature resides in the particular construction of such a boiler as is mentioned in the preceding paragraph, and wherein an exterior vapor receiving and condensing shell houses the major portion of a steam generating or heat absorbing unit for converting water into steam, and in which combination the parts are so arranged that the connections to the heat absorbing unit may be entirely outside the vapor containing shell, thereby eliminating many joints which would otherwise have to be made vapor-tight; and, also, so mounting the heat absorbing unit with respect to the shell that it may expand and contract both longitudinally and transversely without disarranging the parts or producing vapor leaks.

The invention will be understood from the description in connection with the accompanying drawings in which Fig. 1 is a vertical section through an illustrative embodiment of the invention; Fig. 2 is a section partly broken away along the line 2—2 of Fig. 1; Fig. 3 is a section showing one of the details. Fig. 4 is a section along the line 4—4 of Fig. 1; and Fig. 5 is a similar section through a modification.

In the drawings reference character 1 indicates a casing or cylindrical shell that is provided with an inlet 2 at one end thereof for mercury vapors. An outlet 3 for condensed mercury is provided at the bottom.

The shell 1 is supported upon supports 4 near opposite ends and an upper drum 5 ex-

tends into the shell through one end and projects to some distance outside of the shell. A similar lower drum 6 smaller than the drum 5 is also provided and extends through the same end of the shell 1. A valved drain pipe 7 may be provided at the bottom of the drum 6 outside of the shell 1. A feed pipe 8 enters the end of the upper drum 5 that extends outside of the shell 1 and the feed pipe 8 extends substantially entirely through the drum 5 and is supported upon cross supports 9 at intervals. A water level indicator 10 and safety valve connections 11 are provided on the portion of the drum 5 that extends outside of the shell. A dry pipe 12 supported by straps 13 is located in the upper or steam space of the drum 5 and the outlet 14 from this dry pipe extends through the upper surface of the extending end of the drum 5.

Rows of bent tubes 15 connect the drums 5 and 6 on the inside of the casing 1 and the ends of these tubes enter both drums radially. The upper drum 5 is supported upon cross supports 16 and the lower drum 6 is supported from the drum 5 by means of the tubes 15 and is free to move up and down when the tubes contract and expand. A flexible seal 17 is provided between each drum 5 and 6 and the casing 1 where the drums pass through the casing. A portion of the seal 17 is shown in Fig. 3 on an enlarged scale. The seals 17 are between the parts, namely, the drums 5 and 6 which are in contact with the water or steam on one side and vapor on the other side and the shell 1 which is in contact with vapor only, so that difference in expansion between them may take place without causing leakage, that is, there are flexible seals between the steam boiler and the vapor condenser shell. The mercury vapor shell 1 can increase in diameter in starting up with cold water in the drums 5 and 6 without causing leakage to take place due to difference in expansion.

In the modification shown in Fig. 5, only one drum, namely, the steam and water drum 5 extends into the casing 1 and a portion of this drum on one side of a vertical plane through the drum is connected by rows of curved tubes 15' to a similar portion of the

drum upon the other side of the plane, the ends of the tubes entering the drum on radial lines.

The operation is as follows: Feed water is supplied through the feed pipe 8, which may be provided with distributed openings in the drum 6, and the drum 5 is kept about half filled with water which also fills the tubes 15 and the drum 6. Vapors of a high boiling point liquid are introduced into the casing 1 through the inlet 2 and condensing around the tubes 15 and the drums give up heat which generates steam from the water in the drums 5 and 6 and tubes 15. The condensed vapor passes out through the outlet 3. The steam collects in the steam space of the upper drum and passes out through the dry pipe 12 and outlet 14 to the place of use.

I claim:

20 1. In a device of the character described, a shell, and a heat absorbing unit having drums disposed with their major portion within the shell and passing through only one wall thereof whereby relative expansion and contraction of the shell and drums longitudinally are taken care of, water tubes connecting the drums wholly within the shell, flexing expansion and contraction collars, one united in vapor-tight relation to each drum peripherally and to the shell, and connections for fluids, those of the drums being exteriorly of the shell.

25 2. In a device of the character described, a shell, and a heat absorbing unit having drums disposed with their major portion within the shell and passing through only one wall thereof whereby relative expansion and contraction of the shell and drums longitudinally are taken care of, water tubes connecting the drums wholly within the shell, flexing expansion and contraction collars, one united in vapor-tight relation to each drum peripherally and to the shell, and connections for fluids, those of the heat absorbing unit being wholly exteriorly of the shell and on the upper drum.

30 3. In a device of the character described, a shell, and a heat absorbing unit having a steam and water drum disposed with its major portion within the shell and passing through only one wall thereof whereby relative expansion and contraction of the shell and drum longitudinally are taken care of, water tubes wholly within the shell and providing circulation to and from the steam and water drum, flexing expansion and contraction collars, one united in vapor-tight relation to each drum peripherally and to the shell, a steam separating tube within the drum and having its connection to the drum exteriorly of the shell, a water feeding tube interiorly of the drum and having its connection exteriorly of the shell.

35 4. In a device of the character described, a shell, and a heat absorbing unit having a

steam and water drum disposed with its major portion within the shell and passing through only one wall thereof whereby relative expansion and contraction of the shell and drum longitudinally are taken care of, 70 water tubes wholly within the shell and providing circulation to and from the steam and water drum, flexing expansion and contraction collars, one united in vapor-tight relation to each drum peripherally and to the shell, a steam separating tube within the drum and having its connection to the drum exteriorly of the shell, a water feeding tube interiorly of the drum and having its connection exteriorly of the shell, and a manhole in the 80 drum exteriorly of the shell.

5. In a device of the character described, a shell, and a heat absorbing unit having drums disposed with their major portion within the shell and passing through only one wall thereof whereby relative expansion and contraction of the shell and drums longitudinally are taken care of, water tubes connecting the drums wholly within the shell, flexing expansion and contraction collars, one united in vapor-tight relation to each drum peripherally and to the shell, and connections for fluids, those of the drums being exteriorly of the shell.

6. In a device of the character described, a shell, and a heat absorbing unit having drums disposed with their major portion within the shell and passing through only one wall thereof whereby relative expansion and contraction of the shell and drums longitudinally are taken care of, water tubes connecting the drums wholly within the shell, flexing expansion and contraction collars, one united in vapor-tight relation to each drum peripherally and to the shell, and connections for fluids, those of the heat absorbing unit being wholly exteriorly of the shell and on the upper drum.
